LIGHTING FIXTURE

Arthur E. Wiedenhoeft and Harry A. Best,
Chicago, Ill.

Application June 24, 1932, Serial No. 619,058

13 Claims. (Cl. 240—81)

This invention relates in general to a lighting fixture combining the use of gas filled tubing and ordinary filament electric lamps and has more particular reference to a pedestal or floor lamp but may also be applied to an inverted type of pendant lamps or fixtures.

One of the principal objects of the invention is in the provision of a lighting fixture in which gas filled tubing is combined with filament electric lamps to provide an improved type of electric lighting fixtures.

A further object of the invention is in the provision of a supporting stem for lighting fixtures which is illuminated by an electrified gas filled tubing.

A further object of the invention is in the provision of a floor lamp in which a transformer for a gas filled tubing lamp is combined in a floor supported lamp.

A still further object of the invention is in the provision of light reflecting tubing combined with a gas filled tubing light, the tubing light being either within or without the other tubing which is illuminated thereby to produce a more attractive lighting effect.

A still further object of the invention is in the provision of a lighting fixture support in which glass and metal tubings are combined and secured together for producing novel lighting effects, for mutually strengthening each other, and for providing passageways for conductors, all for the purpose of producing a lighting fixture of novel type, design and combinations.

Other objects of the invention will appear hereinafter, the preferred construction and modifications thereof being illustrated in the accompanying drawing. In the drawing,

Fig. 1 is a sectional view of a lighting fixture in accordance with this invention;

Fig. 2 is a section taken on the line 2—2 of Fig. 1;

Fig. 3 is a similar section of a modification; and

Fig. 4 is another section of a modification.

In the ordinary type of floor lamp it is customary to support a shade at a distance from the floor or support by means of a hollow rod or stem through which the conductors extend for supplying current to the lamps. The supporting tube is usually plain and unattractive and of course has no lighting value.

The present invention proposes to utilize a gas filled tubing type of lamp for illuminating the supporting stem thereby making it attractive in appearance either separately or in combination with filament lamps which are enclosed or covered by

the shade. This type of supporting stem is capable of a great modification and variation by means of which entirely different and novel lighting effects may be obtained.

Referring now more particularly to the drawing, a floor lamp is illustrated in Fig. 1 having a hollow metallic base portion 6 supported by legs 7 and with an upper shade or reflector 8 suitably supported in any well-known manner as from a central stem 9 and enclosing a number of electric lamps 10 of the filament type. The shade 8 may be of any suitable transparent, opaque or reflecting material of which such parts are made.

Extending between the base and the shade 8 is a supporting standard comprising a central tube 11 of transparent material such as glass providing a protected bore 12 for a neon or gas filled tubing 13. The outer surface of the tube 11 may be provided with flutings 14 or other decorations and when the gas filled tubing is electrified a beautiful glow and illuminating effect is produced by the tubing 11.

At intervals along the tubing 11 are supporting rings 15 for solid and hollow rods 16 and 17, each ring 15 having portions 18 for surrounding or engaging the rods and holding them in place. The rings themselves are held in place by screws 19 which are inserted through the ring 15 and through the solid rod 16, if desired, into receiving recesses 20 in the tube 11.

The supporting standard is secured to and upheld at its lower end by fastening devices 21 which extend through the rods 16 and upper flanges at the base 6, or by any other suitable connection, and at the upper end of the standard is a frame or receptacle 22 preferably of sheet metal, which may be secured at the upper ends of the rods 16 and 17 in any suitable manner as by means of threaded portions 23 and lock nuts 24 engaging the inner and outer sides of the receptacle. This receptacle provides a support for the attachment of lamp brackets 25 and also for an upper socket 26 for the gas filled tubing 13. The central stem 9 for supporting the shade 8 may be attached to the top or cover 27 of the receptacle 22 and removable bodily with it if desired to uncover the receptacle.

At the lower end of the standard and within the base 6 is a lower socket 28 for the gas filled tubing 13. Also carried by the base 6 is an extension 29 for housing a transformer 30 for supplying current under high voltage to the sockets 26 and 28 for the gas filled tubing 13. This transformer receives current from the ordinary conductors 31 which supply current to the filament

lamps 10, the conductors passing upwardly through one of the hollow tubes 17. A secondary or high voltage current from the transformer is connected to the sockets 26 and 28 by means of conductors 32 and 33, one of which also extends through one of the hollow tubes to the upper socket 26. By separately controlling the filament lamps and the gas filled tubing entirely different lighting effects may be produced and by making the gas filled tubing 13 separate from the hollow tubing 11, the gas filled tubings for producing colors when electrified may be interchangeable. Instead of having a supporting standard as shown in Figs. 1 and 2, various modifications may be employed for producing similar but different lighting effects. As shown in Fig. 3, a solid glass bar 35 having fluted or decorated edges 36 may be provided at opposite sides with gas filled tubings 37 and 38 for producing the same or different colors, these tubes being protected and partially enclosed by metallic shields 39 which confine the light from the tubings toward the bar 35 which will receive, reflect and disperse the light therefrom in a highly attractive and pleasing manner. This arrangement provides spaces between the bar and the tubings for conductors 40 by means of which the upper lamps and sockets are supplied with current.

In the modified form of standard as shown in Fig. 4, three solid glass bars 42 partially enclose and protect a central gas filled tubing 43 with a number of hollow metal tubes 44 disposed therebetween for securing the parts together and for providing protected passageways for conductors 45.

Other combinations of hollow and solid bars and tubes of glass, pipe and reflecting material may be connected to form standards which are illuminated when desired by means of one or more glass filled tubings of the same or similar color, the tubing lamps producing a lighting effect which is attractive and novel in appearance and is made variable by variously lighting the tubes themselves and by interchanging the tubes when desired. It should also be understood that a confining or strengthening ring similar to the supporting ring 15 may be provided at intervals for securing the various bars and tubes together thereby adding a decorative effect, preventing the parts from becoming loose or spaced apart throughout their length, and also providing means for mutually strengthening and supporting the associated parts which make up the standard or stem which constitutes this part of the fixture.

The lighting transformer is included as a part of the fixture enclosed in the base and the sockets for the gas filled tubing are located in parallel relation one above the other so that this tubing may be easily removed and interchanged.

We claim:

1. In a lighting fixture, a main illuminating portion comprising a shade or reflector, and electric lighting means; and a reflecting and refracting supporting stem of considerable length and an exterior lamp of gas filled tubing which illuminates the entire stem when electrified.

2. An electric fixture comprising a main illuminating portion, and a supporting glass standard therefor of considerable length comprising an outside tubing lamp which illuminates the standard throughout its length.

3. In a lighting fixture, a relatively thin supporting and illuminating stem comprising a gas filled tubing lamp and a reflecting and refracting bar co-extensive with the tubing and closely con-

tiguous thereto for modifying the light therefrom when it is lighted.

4. In a lighting fixture, an illuminating standard comprising a tubing lamp and co-extensive bars of glass and metal secured together and providing a stem for reflecting and refracting light from the tubing and supporting it throughout its length.

5. In a lighting fixture, an illuminating supporting stem comprising a tubing lamp, bars of glass and metal co-extensive with the tubing lamp, and means securing the bars together forming a stem for supporting the lamp and reflecting and refracting the light therefrom.

6. In a lighting fixture, a main illuminating portion, a supporting stem therefor comprising a tubing lamp, glass and metal bars closely associated to form a supporting stem with the tubing lamp and receiving illumination therefrom and including a hollow bar with conductors extending through it to supply current to the main illuminating portion and to the tubing lamp terminal adjacent thereto.

7. In a lighting fixture, an illuminated standard comprising a tubing lamp, glass and metal bars associated therewith to form a supporting stem, and means for confining the bars and tubing together at their ends and intermediate the ends for providing a relatively thin standard of sufficient supporting strength, the lamp illuminating the bars throughout the length of the standard.

8. In a lighting fixture, a main illuminating portion, a base and a supporting standard between the illuminating portion and the base, the standard including a tubing lamp extending throughout the length of the standard and comprising a socket in the main illuminating portion, and a similarly facing socket in the base but out of line with the other socket to which the ends of the tubing are connected by a single movement thereof in one direction for receiving current.

9. An electric fixture comprising a main illuminating portion, a supporting base, a standard or stem of considerable length connecting the said portion and base, filament lamps in the main portion, the stem comprising a tubing lamp extending from the base to the main portion and glass and metal bars parallel with and connected to the tubing for supporting it throughout its length, the tubing lamp illuminating the glass and metal bars throughout the length of the stem, conductors extending from the base through the stem to the main portion for lighting the filament lamps and the tubing.

10. In an electric fixture, a main illuminating portion, an illuminating stem for supporting the main portion, a base for supporting the stem, a tubing lamp extending throughout the stem and having parallel and similarly facing terminals in the main portion and base of the fixture so that it may be readily removed therefrom in one direction, means for supplying current through the stem to the socket in the said main portion from the base of the fixture.

11. A floor lamp lighting fixture of the combined filament and electrified tubing type comprising a main illuminating portion having a shade or reflector, filament lamps enclosed therein, a receptacle or frame by which the lamps are supported, an illuminating stem secured at one end to the receptacle or frame, a base connected at the other end of the stem, the illuminating stem comprising a gas filled tubing, an upper socket for the tubing in the receptacle at one

side of the stem, another socket for the tubing in the base, the tubing having a reverse bend at its upper end within the receptacle whereby the sockets are parallel and open in the same direction so that the tube is easily removed therefrom.

12. An electric fixture comprising a main illuminating portion, a standard therefor including a gas filled tubing lamp, a supporting base for the standard, spaced sockets for the tubing lamp, one located in the main illuminating portion and the other parallel thereto but not in line therewith in the base, the sockets facing in the same direction for applying and removing the lamp, and a transformer carried by the base and having connections through the standard to the

socket in the main portion and to the socket in the base.

13. In a lighting fixture, the combination of a main illuminating portion, a supporting stem, a base for supporting the stem, a tubing lamp extending from the base co-extensive with the stem and terminating in the main portion, the tubing having a reverse bend at one end and sockets for the tubing located in the base and in the main portion out of alignment but parallel and opening in the same direction whereby the tubing lamp may be inserted and removed from the sockets and with respect to the stem by a single movement in one direction.
